[57] CLAIM

The ornamental design for a combined wristwatch and calorie counter, as shown and described.

DESCRIPTION

FIG. 1 is a top, front and left side perspective view of a combined wristwatch and calorie counter showing my new design;

FIG. 2 is a top plan view;

FIG. 3 is a front elevational view, the rear elevational view being a mirror image thereof; and

FIG. 4 is a right side elevational view thereof.

FIG. 1

FIG. 2

FIG. 3

FIG. 4
